ATTORNEY.

UNITED STATES PATENT OFFICE.

ALBA C. HONEYCUTT, OF WICHITA, KANSAS.

MAGNETO PLUG.

Application filed December 9, 1922. Serial No. 605,903.

My invention relates to magneto plugs for internal combustion motors in which is embodied certain construction for simplicity of assembly and installation.

5 The object of my invention is to construct a plug, having an insulator held in position by a metallic sleeve and an annular ring base, with adjusting means, with oil proof features.

10 A further object of my invention is that the spring tension for the post be made of copper, and simple to remove for cleaning.

With the foregoing and other objects in view, my invention consists in details of 15 construction and in general arrangement of parts combined which are hereinafter more fully set forth and claimed.

In the detailed description of my invention reference will be had to the accompanying 20 drawings which form a part of this application, and similar figures will refer to similar parts in the various drawings.

Fig. 1 is a sectional view of the magneto plug in its proper position. Fig. 2 is a top 25 view of the annular ring base. Fig. 3 is a sectional view showing the scope of adjustment.

In Fig. 1, 1 is a fragment of a magneto case, 2 is a fragment of the coil frame, 3 is 30 the contact point, 4 is the copper spring, 5 is the magneto post passing through said coil 4 and the insulator 6, top of said post being threaded to receive a nut 7 for tensioning and holding in proper place, the magneto post 5. 8 is a nut with knurled rim, adapted to bind the ground wire 9 between said nut and nut 7. 10 is a metal sleeve preferably made of aluminum, said sleeve is adapted to receive the insulator 6, holding it oil tight 35 by reason of the tapering form of said insulation and a similar taper of the bore of sleeve 10, which occur approximately between the dotted lines indicated in Fig. 1. 11 is an annular base, said base being 40 fastened to magneto case 1, by means of screws 12, said base, being placed concentric to a hole, through the magneto case which is adapted to receive the insulator 6. The said base has an annular tongue 13, adapted 45 to register in an annular groove 14, which is in the sleeve, heretofore referred to, the object of which is to allow for an adjustment to increase or decrease the tension of

said contact point 3 on the coil frame 2. Should proper tension be acquired without 55 closing the joint 15 between said sleeve and collar, the tongue 13 will function as a stop to prevent oil passing out, or dust approaching the threads as shown at 16.

The coil spring 4 is made of copper, being 60 soldered to the contact point 3, and seated on a washer at 18, in the insulator. My object in making this spring of copper is that it will not be necessary to remove the plug when the magneto is being charged, 65 the electric current will not retard the tension of a copper spring as it will in the case of a steel spring, therefore it will not be required to remove my magneto post while charging the magneto. 70

As a preventative for oil passing up the magneto post, and out through the top of the insulator, I have provided a close fitting fiber washer on the stem 5, as shown at 18. 19 is the hexagon flange of the sleeve 75 adapted to receive a wrench and in which is placed the annular groove 14. In the course of construction to assemble the parts of my newly invented magneto post, I enter the insulator at the base of the sleeve and 80 it is forced into the taper of said sleeve, making it oil tight, then I insert the magneto post and spring at the lower end, passing them through the insulation, then by applying the nut 7 to the post 5 and running 85 it down against the top of said insulator, I tension the spring until the contact point protrudes approximately as shown in Fig. 1. I then place the collar 11 on the magneto case, fastening it firmly as heretofore described, and then I enter the sleeve, screwing 90 it down to the distance required for good contact on the coil frame 2 and for this process, a wrench may be used.

The ground wire 9 may be looped or have 95 a washer soldered thereto with an aperture to pass over the post 5 and resting on the nut 7, I then screw a nut 8, binding said connection firmly between said nuts 7 and 8.

Such modifications may be made on the 100 various parts as lie within the appended claim.

Having thus described my invention, what I claim as new and desire to secure by Letters Patent is;

In magneto plugs, a collar having a

threaded aperture concentrically positioned, an annular tongue paralleling the threaded aperture and spaced outward therefrom, a sleeve having a threaded extension to engage 5 in the aperture of the collar, the outer end of the sleeve converging, an annular outward extension of the sleeve having an annular

groove therein to engage with the tongue on said collar, a magneto post insulator having a taper on the outer end thereof to engage 10 in the sleeve as means for longitudinal adjustment by the rotation of the sleeve.
